UNITED STATES PATENT OFFICE.

MICHAEL W. McARDLE, OF CHICAGO, ILLINOIS.

SHEEP SHEAR.

Application filed March 18, 1927. Serial No. 176,377.

The purpose of this invention is to provide in a power driven sheep shear and like implements, guidance for the reciprocated blade against movement on the fixed blade calculated to defeat the tendency of the driving means, which usually comprises a crank and cam, to sway or slightly oscillate the reciprocated blade transversely of its path of reciprocation, which tends to cause lateral wear on the guide feature travelling therein toward the middle portion of the length and thereby render the cutting value of the stroke variant as between the middle and the end portions of the fixed blade or comb.

A further purpose of the invention is to provide replacement parts for the wearing surfaces involved in the service of the reciprocating blade. It consists in the elements and features of construction shown and described as defined in the claims.

In the drawings:

Figure 1 is a fore-and-aft section of a power driven sheep shear embodying this invention;

Figure 2 is a bottom plan view of the same; Figure 3 is a top plan view with the fixed casing of the sheep shear partly broken away to disclose the entire construction;

Figure 4 is a section at the line 4—4 on Figure 1;

Figure 5 is a section at the line 5—5 on Figure 1.

Figures 6, 7 and 8 are plan views of sheet metal blanks from which certain removable wear plates for the slide bearings are formed.

Figures 9, 10 and 11 are perspective views for showing the completed form of the parts made from the blanks shown in Figures 6, 7 and 8 respectively.

Figure 12 is a detail perspective view showing the wearing parts represented in Figures 10 and 11 in their working positions with respect to the blade.

Referring to the drawings; the fixed casing of the shear is indicated at A; the power shaft is indicated at B having a crank member, B¹, with a crank wrist, b¹. The fixed blade or comb is indicated at D; the reciprocating blade is indicated at E; F is a cam plate carried by the reciprocating blade having a vertical slot f which is engaged by the crank wrist b¹ of the power crank B. The parts described are held in assembled relation by a bolt G inserted from the under side through the fixed blade in which the squared

shoulder, g, of the bolt engages the square aperture in the blade, the bolt extending up through the reciprocating blade which is apertured as seen at, e, to permit reciprocation, and thence through the fixed casing, A, above which the bolt protrudes for receiving a spring, G², and nut, G¹, above the spring for adjusting the spring to proper tension for holding the parts in the necessary snug relation to each other for effective shearing action of the blades.

The reciprocation of the blade E, it will be understood, is effected by the engagement of the crank b¹ in the slot f of the cam plate F, said cam plate being mounted rigidly on the reciprocating blade E. The blade E has a forwardly facing longitudinally extending shoulder 20 which cooperates with downwardly extending projections 21 at the forward edge of the casing, said projections being situated at the opposite ends of the downwardly projecting flange or lip, 25, of said casing, each projection 21 being longer than the cutting stroke of the blade E. This is a familiar construction for affording guidance for the reciprocating blade with a tendency to counteract somewhat the tendency of the crank and cam drive described, to sway or oscillate the reciprocating blade transversely of its direction of stroke as the crank wrist encounters the cam slot alternately at the opposite sides for giving the blade its operative stroke. This expedient for preventing the oscillation of the blade has not been found satisfactorily effective because the vertical plane of the guidance of the reciprocating blade afforded by the projections 20 is so far offset forwardly from the vertical plane of action of the crank wrist as to create a leverage in favor of the frictional engagement of the crank wrist with the cam faces operating alternately for swinging opposite ends of the cutter back and forward.

In the present construction this defect is obviated by providing guidance for the reciprocating blade upon the fixed blade directly in the vertical plane of actuation of the blade by the engagement of the crank wrist with the cam. For this purpose, the fixed blade has two aligned apertures, 30—30, near its opposite ends which are engaged by downwardly extending projections, 35—35, which may be considered projections of the reciprocating blade, but which are in fact formed as projections from the cam plate, F, at the op-

posite ends thereof, said projections extending through the reciprocating blade, E, and constituting part of the means of securing the cam plate to said fixed blade rigidly, as 5 stated, such securement being further effected by tenons, 34—34, entering registered apertures, 33—33, in the middle part of the length of the blade, and a screw, 36, at the middle of the length of the blade engaging the cam plate 10 at the lug, 39, infolded at the lower end of the cam slot, f. The projections, 35—35, it will be seen, are positioned substantially in the vertical plane of encounter of the crank wrist with the sides of the cam slot for actuating 15 the blade; and in consequence, there is no tendency to oscillation of the blade in the plane of its cutting action resulting from the driving action of the crank wrist.

Further details of the construction consistent 20 with this feature, comprise the engagement of the fixed blade with the casing. This engagement is effected by the downwardly extending projections 50 at the rear edge of the casing, engaging apertures, 51—51, and 25 the provision on the rear edge of the casing intermediate the two projections, 50—50, of a slight downwardly curved projection, 53, on which the fixed blade may rock slightly in the manner and degree which is permitted by the 30 fit of the projections, 51—51, in the apertures, 52—52, of the plate. This feature is familiar in tools of this character and is not a part of the present invention except that the present invention consists in this feature so that 35 neither prevents the functioning of the other.

The second feature of the present invention consisting in the provision of replaceable wearing parts at the slide bearings and engagements for guidance of the reciprocating 40 blade, comprise the following, which will be described in the order of their probable relative importance.

For effectively preventing the oscillation of the reciprocating blade, it will be obvious 45 that play or possibility of movement of the blade with respect to the projections, 35, which engage the slots, 30, laterally with respect to those slots, must be kept at the minimum consistent with the sliding movement of 50 the projections in the slots; and it will be obvious that a very limited amount of lateral wear in the slots tending to widen them will be fatal to the function of the construction for preventing oscillation of the blade, and 55 also that such wear will be very difficult to correct; and in fact, cannot be corrected without drawing the temper of the blade and subjecting it to some means for upsetting the metal around the slots. This is an impractical 60 method and it is therefore very important to provide other means tending to prevent wear of the projections upon the sides of the slots. For this purpose, there is shown mounted upon the under side of the fixed blade, D, a 65 steel stamping, J, made from a quite thin

sheet steel blank, seen in Figure 6, which is formed by cutting the metal at lines, 65 and 66, and striking the metal up to form parallel upstanding lips or lugs, 67—67, and forming an aperture, 68, between them, said lugs or lips being dimensioned and spaced apart for entering and fitting in the slots, 30—30, respectively, when the stamping is applied upon the under side of the blade, D, to which it is held by lugs, 58—58, folded up at the ends of said stamping for clasping the ends of the blade D, said blade being formed with slightly beveled notches, 59—59, for engagement of the upturned lugs, 58—58, the latter leaning slightly inward for engaging the beveled edges of the notches into which the elasticity of the stamping permits the said upturned lugs to be snapped in applying the stamping to the blade as described. It will be understood that when this stamping, serving as a wear piece, is applied to the blade, the slots in which the upturned lugs enter for lining the same at the sides exposed to wear, will be made enough wider than the projections, 35, which engage the slot, to accommodate the said lining lips of the wear piece, which will be suitably spaced apart to admit the projections, 35, between them.

A removable and replaceable wear piece on the reciprocating blade at its path of sliding contact with and pressure against the projections, 21—21, at the ends of the lip, 25, of the casing, is provided, formed from the thin sheet steel blank, 70, shown in Figure 7, which is folded at the dotted line, 71, into angular form dimensioned for lodgement in the angle between the upper face of the blade E and the shoulder, 20, by which the blade is stopped against the projections, 21—21, said wear piece being removably held to the blade, E, by downturned lugs, 72—72, at its opposite ends, which engage slightly beveled undercut notches, 75—75, formed at the ends of the blade E, the said lugs being slightly inclined inward and adapted to snap into the beveled undercut notches so as to be safely retained on the blade as against any tendency to displace it, either longitudinally or laterally.

The casing A, being cast metal, the projections, 21—21, against which the reciprocating blade is stressed by the tension spring, G², holding the fixed blade against the reciprocating blade, when said projections are wholly formed as part of the casting, their wear beyond a certain degree necessitates replacing the entire casing. It is therefore very desirable that the pressure and wear-receiving projections should be made separate from the casting so as to be removable and replaceable. This is accomplished by forming the projections substantially as to their entirety by means of clips, 80—80, made of suitably dimensioned blanks of steel shown in Figure 8, which is folded at dotted lines, 81—81 into channel form dimensioned for 130

embracing the lip, 20, of the casing and having struck inward from both flanges of the channel, pointed projections, 82—82, which engage correspondingly slight countersinks, 5 84—84, made in the face of the casing so that these clips may be snapped onto the lip 21, and retained thereon safely against displacement during use.

It will be understood in respect to all the 10 wear pieces above described that when they become sufficiently worn to impair the operation of the tool, they can be manually removed and discarded, and replaced by duplicates which will be furnished with the tool 15 for such substitution, thereby dispensing with the necessity for refitting or replacing the worn parts of the tool which could be done only at much greater cost.

I claim:

- 20 1. In a sheep shear and like tool having fixed and reciprocating blades co-operating for shearing, a casing in which they are mounted for reciprocation one upon the other, and parts affording sliding engagement between said blades for guidance of the reciprocating blade upon the fixed blade comprising a sheet metal wear piece removably engaged with the fixed blade and positioned for such engagement substantially in the 25 plane of the cut at the intersection therewith of the vertical plane of the engagement of the reciprocating blade for actuation, said slide engagement being effected by longitudinally extending slots in the fixed blade and projections from the reciprocating blade engaging said slots, and the wear piece consisting of a sheet metal strip applied to the under side of the fixed blade having lips struck up into the slots for lining the latter at its opposite 30 longitudinal sides and having lugs at the ends folded up for engagement with the ends of the blade.
2. In a sheep shear and like tool having fixed and reciprocating blades co-operating for shearing, a casing in which they are mounted for reciprocation one upon the other, and parts affording sliding engagement between said blades for guidance of the reciprocating blade upon the fixed blade comprising a sheet metal wear piece removably engaged with the fixed blade and positioned for such engagement substantially in the plane of the cut at the intersection therewith of the vertical plane of the engagement of the reciprocating blade for actuation, said slide engagement being effected by longitudinally extending slots in the fixed blade and projections from the reciprocating blade engaging said slots, and the wear piece consisting of a sheet metal strip applied to the under side of the fixed blade having lips struck up into the slots for lining the latter at its opposite longitudinal sides and having lugs at the ends folded up for engagement with the ends of the blade, the latter having 35 notches at the ends for engagement by said upturned lugs.
3. In a sheep shear and like tool having fixed and reciprocating blades co-operating for shearing, a casing in which they are mounted for reciprocation one upon the other, and parts affording sliding engagement between said blades for guidance of the reciprocating blade upon the fixed blade comprising a sheet metal wear piece removably engaged with the fixed blade and positioned for such engagement substantially in the plane of the cut at the intersection therewith of the vertical plane of the engagement of the reciprocating blade for actuation, said slide 40 engagement being effected by longitudinally extending slots in the fixed blade and projections from the reciprocating blade engaging said slots, and the wear piece consisting of a sheet metal strip applied to the under side of the fixed blade having lips struck up into the slots for lining the latter at its opposite longitudinal sides and having lugs at the ends folded up for engagement with the ends of the blade, the latter having beveled shoulders at the ends for engagement of said upturned lugs, the latter being slightly inclined inwardly correspondingly to the bevel of said shoulders.
4. In a sheep shear and like tool, comprising a casing, a fixed blade thereon, and a reciprocating blade mounted therein for co-operation with the fixed blade, means for holding the blades yieldingly in shearing contact with each other, the reciprocating blade having a longitudinal guide shoulder and the casing having a longitudinally extending lip bearing upon the reciprocating blade for receiving the pressure by which the two blades are held in contact and cooperating with said guide shoulder in the reciprocation of the blade; a removable wear piece at the slide bearing of the reciprocating blade against said lip, consisting of a sheet steel strip having at its ends lugs folded to 50 clasp the ends of the reciprocating blade, the latter having notches for engagement of said clasping lugs.
5. In a sheep shear and like tool comprising a casing, a fixed blade thereon, and a reciprocating blade mounted therein for co-operation with the fixed blade, means for holding the blades yieldingly in shearing contact with each other, the reciprocating blade having a longitudinal guide shoulder and the casing having a longitudinally extending lip bearing upon the reciprocating blade for receiving the pressure by which the two blades are held in contact and cooperating with said guide shoulder in the reciprocation of the blade for the slide bearing of the casing lip upon the reciprocating blade and its guide shoulder consisting of a sheet metal strip folded in angular form for fitting the angle between said shoulder and the 55 60 65 70 75 80 85 90 95 100 105 110 115 120 125 130

- face of the blade and having at its ends lugs for clasping the ends of the blade, the blade having notches for engagement of said clasping lugs.
- 5 6. In a sheep shear and like tool having fixed and reciprocating blades co-operating for shearing, a casing in which they are mounted for reciprocation one upon the other, the casing having a lip bearing upon
- 10 the reciprocating blade having wear pieces

at its opposite end portion consisting of sheet metal channel-formed clips adapted to be applied over the lip, said clips and the lip being cooperatively formed for snap engagement of the clips with the lip.

15

In testimony whereof, I have hereunto set my hand at Chicago, Illinois, this 15th day of March, 1927.

MICHAEL W. McARDLE.
